UNITED STATES PATENT OFFICE.

MILTON E. WINANS, OF NEWARK, NEW JERSEY.

IRONING MACHINE.

Application filed November 8, 1919. Serial No. 336,601.

To all whom it may concern:

Be it known that I, MILTON E. WINANS, a citizen of the United States, and a resident of Newark, in the county of Essex and State of New Jersey, have invented new and useful Improvements in Ironing Machines, of which the following is a specification.

This invention relates especially to that class of ironing machines which are intended for use in private families, and the objects of the invention are to provide an improved and simplified construction which can be produced at a price within reach of the ordinary family, which can be used efficiently without great liability of getting out of order, and which is simple and easily operated. More particularly, the objects of the invention are to secure improved movement of the roller toward and away from a stationary heated ironing shoe, and to obtain such movement in substantially a radial line of the curved ironing surface of the shoe; to thus enable the space between the roller and shoe to be quickly varied, and avoid likelihood of the clothes jamming and being held stationary so that they scorch or burn; to secure an improved construction of roller, by means of which its ends are bound so that it is more permanently secured and is automatically centered; to secure an improved clothes rail, and to obtain other advantages and results as may be brought out in the following description.

Referring to the accompanying drawings, in which like numerals of reference indicate the same parts throughout the several views,

Figure 1 is an end elevation of an ironing machine of my improved construction;

Figure 2 is a transverse section of the same at its middle, on line 2—2 of Fig. 3;

Figure 3 is a front elevation, with the clothes rail swung open;

Figure 4 is a plan, with the clothes rail closed.

Figure 5 is a detail view of the mounting of said clothes rail, and

Figure 6 is a detail section of one end of the ironing roller.

In said drawings, 1, 2 indicate opposite end frames of my improved ironing machine which are preferably cast with an angle iron formation and provide feet 3 to rest upon the floor. Near said feet, or at the lower ends of the frames, they are connected by front and rear angle iron cross

bars 4, 5 extending the length of the machine from one frame to the other, and at a higher point of the machine are other similar angle iron cross bars 6, 6 which also serve to connect the end frames, so that the machine will be rigid. Preferably the lower angle bars 4, 5 are connected to the side frames 1, 2 by means of transverse lugs 7 cast in the angles of the frames and slotted to receive bolts 8 through them and one flange of the angle iron, the other flange of the angle iron being bolted to the flange of the leg by a bolt 9. The upper angle bars 6, 6 are similarly secured by means of flanges or ribs 10, one on the inside of each side frame and extending horizontally along the middle of a connecting portion 11 of the frame. The center board 12 of the lower table of the machine lies upon these flanges or ribs 10, the edge flanges of the angle construction of the side frames overlapping the edges of said board at its ends and lugs 13 cast in the angles of said frames overlying the top of the board at its corners to prevent movement upwardly. Thus when the side frames 1, 2 are connected or secured together by means of the angle bars 4, 5 and 6, 6, the said middle board 12 of the table is secured or held firmly in place and aids in stiffening and bracing the frame of the machine. The tops of the side frames 1, 2 are provided each with an inwardly projecting flange 14, and upon these at the front of the machine is secured the feed table 15 over which the articles to be ironed are inserted.

Arms 16 at the rear edges of the tops of the side frames 1, 2 support a shoe 17 which extends longitudinally of the machine and has a front curved surface 18 against which the clothes are ironed, said shoe being heated by means of a burner tube 19 extending longitudinally of the same and having openings along its length to discharge against the shoe. A perforated shield 20 secured to the rear of the shoe encloses the burner tube 19 and provides a heat chamber. Forward of the said shoe 17, between it and the feed board 15, is the pressure roll 21, which normally lies with its top at about the level of the feed board 15, so that the clothes pass thereover and into the space between the said roll and the heated shoe 17. It will be understood that this roll 21 is padded or covered on its outer surface so as to support the articles to be ironed and carry them

along in contact with the ironing surface 18 of the shoe 17, when the feed roller is pressed against the shoe. The body portion of the roller itself is preferably built up of strips 22 of wood suitably glued together, and at each end a metal cap 23 is slipped over a reduced portion 24 of the roll and is secured thereto by screws 25, see Figure 6. The cap has a hole bored in its center and a trunnion 26 projects from said hole, being driven tightly in place and having an inner head to prevent its escape. This method of fitting a cap over a reduced portion of the body of the roll, which can be turned at the same time as the roll itself, results in the trunnions 26 being central and in alinement without any trouble or pains.

The presser roll is mounted by means of said trunnions 26, 26 in the forwardly and 20 upwardly inclined arms 27, 27 of bell-crank levers 28, 28 which are fulcrumed one on each side frame of the machine just below the shoe 17, as at 29, 44. The points of fulcruming of the bell-cranks are so disposed that when they are swung the presser roll is carried along substantially a radial line of the curved ironing surface 18 and thus moved directly toward and away from said ironing surface. The lower arms 30 of the bell-cranks 28 extend downward one close to each side frame at the inner side thereof and passing through openings in the middle board 12 have forked lower extremities 31 which receive pins on the upper 35 ends of arms 32, 32 fast on a rock shaft 33 extending longitudinally of the machine and journaled in suitable cross pieces 34 near the lower ends of the side frames. At about the middle of said shaft 33 is a forwardly 40 projecting arm 35 which is connected by means of a stiff helical spring 36 to a treadle 37 fulcrumed upon the rear lower angle bar 5 of the machine and projecting under the front angle bar 4 to receive the foot of the operator as at 38. Obviously by these means 45 the presser roll 21 can be swung toward the heated ironing shoe 17, and a spring 39 suitably disposed, as for example extending from the lower end of one of the bell-cranks 50 to the rear edge of its adjacent side frame, serves to normally hold it away from the ironing shoe in idle position, as shown in Figure 2. To enable the presser roll 21 to be locked in various positions adjacent to the ironing shoe 17, to accommodate different thicknesses of articles being ironed, I 55 have provided a stirrup 40 depending from the front angle bar 4 for the treadle 38 to move up and down in and having upon one 60 of its sides stops 41, 41 under which the treadle may be caught at different heights for the purpose stated.

In order to rotate the presser roll 21 one of its trunnions 26 has fast upon its end 65 outside one of the side frames, as for ex-

ample the side frame 2, a gear wheel 42 which meshes with a pinion 43 turning upon the stud shaft 44 upon which the adjacent bell crank 28 is mounted, and said pinion has fast to itself a worm-wheel 45 which 70 engages a worm 46 beneath it fast upon a shaft 47 which projects at the rear of the machine and carries a belt pulley 48. From this pulley 48 a belt 49 extends downward to an electric motor 50 mounted directly on the side frame 2 or ribs 51, 51 upon the inner side of an extension plate 52 of the rear upright of said side frame. A similar extension plate 53 reaching to the top of the side frame affords a bearing for the stub 80 shaft 44, and a broad bracket 54 on the outside of said plate affords another bearing for its outer end, as well as guards the worm-wheel 45 and pinion 43. The bottom of this bracket furthermore is of a box-like formation to receive the worm 46 and provides at its front wall a bearing for the end of the worm shaft 47 and at its rear wall receives a bushing 55 for said shaft, held in place by a set screw 56.

By reason of the pinion 43 which drives the roll 21 being upon the same axial line as the bell-cranks 28 which swing the roll, it is obvious that the roll can be swung without disturbing its drive, the gear-wheel 42 95 simply rolling along the periphery of the pinion 43.

Front and rear leaves 57, 58 slide removably into the same plane as the center board 12 of the lower table which receives the ironed goods as they come from between the roll 21 and shoe 17, said leaves being supported by cleats, 57^a, 58^a respectively, which enter above the angle bars 6, 6 and beneath the center board 12. By this construction, 100 and the mounting of the center board upon the side frames as has been already described, the side frames are enabled to be continuous so that the roll 21 and its driving parts can be accurately lined up with 110 respect to the motor 50 below.

Upon the front edge of the upper part of one of the side frames, as 1, between the two tables, are lugs 59, 59 between which is hinged a removable pin 60 a socket member 61 for a clothes rail 62 which will thus 115 swing into closed position as shown in Figure 4 or open outward for use as shown in Figures 2 and 3. A hole 63 in the feed board 15 in alinement with the pin 60 facilitates its removal and insertion.

Obviously, various detail modifications and changes may be made in manufacturing my improved ironing machine by those skilled in the art without departing from 125 the spirit and scope of the invention, and I do not wish to be understood as restricting myself except as required by the following claims when construed in the light of the prior art.

Having thus described the invention, what I claim is:

1. In an ironing machine, the combination with a shoe, of a presser roll, a rotary member for driving said roll, a bell crank fulcrumed upon the axial line of said rotary member, said presser roll being mounted upon one arm of said bell crank, a rock shaft having a crank arm directly engaging the other arm of said bell crank lever to swing the same, and a treadle connected to said rock shaft to rotate the same.
2. In an ironing machine, the combination of opposite upright end frames, a lever adjacent each end frame fulcrumed to swing in a plane parallel thereto and having one arm projecting upward and the other arm extending downward longitudinally of the end frame to swing back and forth horizontally between the front and back of said end frame, a rock shaft journaled in said side frames below the lower arms of said levers, upwardly extending crank arms on said rock shaft having slot-and-pin connections with said lower arms of the levers, a forwardly projecting arm on said rock shaft midway between said crank arms, a treadle beneath said forwardly extending arm fulcrumed at the rear of the machine and adapted to receive the foot of the operator at the front

of the machine, and a vertically disposed coiled spring connecting the free end of said forwardly extending arm on the rock shaft to said treadle between its fulcrum and foot-receiving end.

3. In an ironing machine, opposite end frames, a table board endwise between said end frames intermediate their tops and bottoms and engaging said end frames, cross bars connecting the end frames beneath said board and clamping the latter in place, said cross bars being spaced from said board, and a removable table leaf having at one lateral edge projecting cleats adapted to be inserted over one of said cross bars and beneath said table board.

4. In an ironing machine, opposite vertical end frames each having at its inner side a horizontal rib, a table board resting at its ends upon said ribs, means for holding said table board against said ribs, cross bars connecting the end frames beneath the table board and secured to the under side of said ribs in spaced relation to said board, and a removable table leaf having at one lateral edge projecting cleats adapted to be inserted between one of said cross bars and the table board.

MILTON E. WINANS.
